GRILL

Alfred L. Greenlaw, New Britain, Conn.

Application June 5, 1942, Serial No. 445,836

3 Claims. (Cl. 98—40)

When introducing air into a room, whether for heating, cooling or ventilation, it is highly desirable that this be accomplished in a manner which will not impart a sensation of draft to persons in the room. Heretofore attempts to avoid sensation of draft have commonly been based on the idea of reducing the velocity of the air entering the room to a low value, and to this end the entering air column has been enlarged in cross section as by the use of ducts flaring outwardly toward the interior of the room, and usually with means for dividing the flow in the desired proportions between the ducts.

The present invention has for an object to produce the same freedom from drafts but by a different method of control which has certain advantages over the method previously described.

In accordance with the method of this invention, the entering air is so controlled that it spreads outwardly close to the surface of the wall in which the outlet opening is placed and it diffuses therefrom into the remainder of the room.

One advantage of this method is that it requires no long tapering air passages. Thus the grill may be used where there is no room for such long air passages. For example, it is possible to set the grill substantially flush with the wall, even when there is little space back of the wall to the end of the distribution duct through which the air is supplied to the room.

A further advantage is that it makes possible the use of a grill having exposed face portions of substantial width, which, in turn, permits the grill to be made with much greater mechanical strength. It is thus practicable to place such a grill in the floor where it may be walked on and may support substantial weight, without injury.

Where no substantial weight is required to be supported by the grill, it may be made of very light construction which can be made very cheaply and with a small amount of material.

The present application is a continuation in part of my application Serial No. 279,443 filed June 16, 1939, for Grills and contains certain subject matter divided out therefrom. The more general aspects of the invention are contained in my application Serial No. 441,897 filed May 6, 1942, now Patent No. 2,341,439, February 8, 1944, also as a continuation in part of my application Serial No. 279,443, to which reference has been made herein.

For a more complete understanding of this invention, reference may be had to the accompanying drawing, in which

Figure 1 is a front elevation of a grill embodying the invention.

Figure 2 is a detail section to a larger scale on line 2—2 of Figure 1.

Figures 3, 4 and 5 are diagrammatic views illustrating critical factors in the grill construction.

Figures 6, 7 and 8 are views similar to Figure 1, but showing modifications.

Figures 9 and 10 are detail sectional views on the correspondingly numbered section lines of Figures 6 and 8, respectively.

Referring first to Figures 1 and 2, a grill is illustrated intended for situations where no substantial weight is to be borne by the grill, as, for example, where the grill is placed in the ceiling or side wall of the room. As shown it comprises a single plate which may be of sheet metal as at 1, cut at intervals along lines generally radiating from the center 2 as at 3 and then transverse to these radial lines as at 4 and 5 so as to define tongues 6 which may be deflected backwardly at an acute angle from the plane of the sheet, there being formed between the deflected portions elongated imperforate portions 7, which as shown radiate from a central imperforate area 8 toward an imperforate margin 9 which may be provided with openings 9a to receive fastening means (not shown) for securing the grill in position. The deflected portions 6 extend backwardly from the outer face of the grill and leave elongated openings 10 for the passage of the air, separated by the imperforate portions 7. The imperforate portion 7 being positioned at one side of each of the deflected portions 6, acts effectively therewith to define an outer side wall 6a for the entering air which is more sharply inclined to the front face of the grill than is the opposed inner side wall 6b formed by the forward face of the portion 6 which defines the opposite side of the air passage. All of the imperforate portions 7 lie in the same plane and form the discharge face at the front of the grill.

The air passing through the openings 10 in this manner produces adjacent to the free edge of each of the imperforate sections 7 a suction effect in conjunction with a critical angle effect between the wall portions 6 and 7 which tends to deflect the air entering the room from the next adjacent passage directly forwardly of the deflected portion 6 in the manner shown by the arrow *a* in Figure 2. This effect is produced successively between adjacent passages around the circumference of the grill, this resulting in the air coming into the

room escaping from the grill in directions along the front face of the wall, the air escaping from the outer surface of this entering air layer into the room so gradually that no effect of draft is noticeable. Thus the air entering the room does so at an angle to the front face of the grill much smaller than the effective discharge angle of the grill passage which would be controlling as to the direction of discharge in the absence of the face of substantial width outwardly of each of the passages. It will be noted that the amount to which the cut portions are turned backwardly and their widths determine the entire thickness of the grill and the widths are determined by the spacing between the radiating lines of cut. Thus the total thickness of the grill may be reduced to a small amount by increasing the number of the cut sections. While the bending back of the cut sections acts to produce a slight spacing of the projection of the free rear edge of the sections on the plane of the front of the grill from the adjacent side of the opening, this rear edge is so far back that the current of air effectually cuts off any straight passage of air perpendicular to the front face of the grill. Such perpendicular passage of air is to be avoided in accordance with this invention, as this would produce a tendency to discharge well into the room rather than causing the discharge to first take place along the wall surface.

The air passing along the walls $6a$ and escaping at the front of the grill produces a lower pressure effect over the front face of the next imperforate portion 7 , causing the air to be discharged laterally across the outer faces of these imperforate or uncut portions, rather than directly out into the room, as indicated by the arrow a , provided that the angle at which the outer walls $6a$ of the tongues 6 are disposed with respect to the imperforate portions 7 and the discharge face of the grill is not sufficient to cause the air to break away from the outer surface of the imperforate portions.

Figures 6 to 10 illustrate constructions wherein in the grill instead of being made from sheet metal is provided with more substantial partitions 15 between the air passages 16 , such as may be made by casting. The rear side face 17 of each of these partitions has an angularity to the perpendicular to the front face of the grill corresponding generally to the rear face $6a$ of the deflected portion 6 of Figures 1 and 2, while the opposite side face 18 is that resulting from more or less filling in between the back faces of the forward walls and the adjacent faces of the rearwardly deflected portions 6 of Figure 1. The precise contour of the filled in portion is of no particular consequence so long as the air is directed thereby against the opposite face of the slot, as will later more fully appear. Figure 6 shows a complete circular series of partitions and openings or slots, while Figures 7 and 8 show half and quarter portions, respectively, which give a less complete arc of diffusion of the air but are particularly suitable for locations where the distribution is otherwise limited as adjacent to angular wall members or near corners of a room.

In all instances it will be noted, however, that the direction of the air discharge from the several slots is in the same direction of rotation about the central axis or axes of the partitions. The central portion of the grill which is shown as closed may be either round or oval as desired, Figure 8 showing a portion of a round center,

while Figures 1, 6 and 7 show the center as elliptical.

The best angles of the faces in all of the constructions shown, depend on various factors, such as width of the faces between the air openings, the smoothness of the side faces of the air passages and the velocity of the air entering.

Certain factors, however, have been found rather critical as follows:

(a) In a grill employing the straight slot arrangement, the length of the slot should be at least 6 inches and the ratio of length to width of the slot should be at least 6 to 1.

(b) However, in a grill employing the radial slot arrangement, the actual length of each slot is not of great importance, because the air is discharged from the grill in a fan-shaped pattern and the effective width of the air stream is many times that of the actual length of the slot.

(c) The angle at the outer side of the slot in sizes of grill larger than six inches diameter cannot be much larger than 50° in order that the jet issuing from the slot will not break away from the contour of the inner wall and may be turned toward parallelism with the discharge face of the grill, and with this angle there must be an effective border or flat wall margin 20 at substantially the plane of the face of the grill, either part of the grill itself, or a wall member in a hole in which the grill is set of at least substantially two inches and three is better, as shown in the diagram of Figure 3. If this angle is reduced, the effective width of the border 20 may be reduced also, and with a 40° angle may be substantially one inch, as shown in Fig. 4. Even with a very wide border, however, the angle cannot be safely increased more than two or three degrees beyond 50° . In this range the jet may become unstable, changing suddenly between substantial parallelism to the face of the grill and outwardly directed at about the angle of the outer wall of the slot. This change in angle is apparently dependent on factors difficult to determine or control. With small size grills such as those of six inches in diameter, the workable angle below the critical is somewhat though not much greater than with the larger sizes. The angularity of the inner wall or face of the slot to the perpendicular to the face of the grill appears to be of no particular consequence so long as the air jet is directed against the outer wall, but in order to so direct the air jet, its sides must either converge toward the outlet or the inner wall member must have a lip or flat section near to its outer edge, or the angle of diversion from the axis of the outer wall must be acute enough to provide this pressure of the air against the outer wall. Where the outer wall does not extend to a point directly back of the inner edge e of the slot, or the forward edge of the inner wall $6b$, the air tends to break away from the contour of the inner wall at a small angle.

In Figure 5 the line z is perpendicular to the outer wall member and the line v joins the back edge of the outer wall member with the forward edge of the inner wall member, forming between them the angle θ . This angle θ is the amount by which the discharge angle is greater than parallel with the outer wall of the slot, line z being parallel with this outer side wall so that the effective discharge angle is represented by the arrow w .

With the radial arrangement of partitions and

air passages shown herein, the air passes into the room with a whirling tendency, the constructions of Figures 7 and 8 causing this tendency to be less than through a complete rotation.

In connection with the present invention, a question may arise in establishing the angle which the inner wall of the member or the outer side wall of the air passage makes with respect to the front face of the grill. For manufacturing, artistic or other reasons, it may be desirable to have either the wall or the face, or both of such design that there would not be any definite angle between the inner wall of the air passage and the front face of the grill, as for example, if the inner side wall of the air passage was concaved or convexed, or the face of the grill was of an irregular nature.

In designs of this character, in order to determine the critical angle for the discharge of air through the passage, it would be necessary to rely on experience or laboratory tests to determine the turning effect of the particular design on an air stream delivered through the air passage. In order to limit the forward face design of the grill and the rearward deflection and depth of the inner side wall and width of the air passage or space between members, to one which will discharge the air laterally and deliver the same substantially parallel with the front discharge face of the grill, I have used a term which I have designated as the critical angle.

The critical angle for the discharge of the air for any opening between the uncut or imperforate portions may be defined as the angle at which the air stream discharged through the opening no longer clings to the contour of the deflected portion 6 and turns in a substantially lateral direction, but breaks away from the contour of the deflected portion and the uncut portion 7, and flows from the front face of the grill into the room in a more nearly axial direction.

From the foregoing description of certain embodiments of this invention it should be evident to those skilled in the art that various changes and modifications might be made without departing from the spirit or scope of this invention.

I claim:

1. A grill comprising a plate provided with a flat front discharge face and having a series of tongue portions struck rearwardly therefrom and defining an arcuate series of air passages separated by imperforate portions arranged around a central portion closed to the outward escape of air, all of the imperforate portions lying in the same plane and forming said front discharge face, one side face of each tongue portion forming an outer wall for an air passage, the other side face of the same tongue portion forming an inner wall for the next adjacent air passage, the inner walls being shaped to direct the air passing through said passages against the

outer walls, the outer walls having an angle with respect to said discharge face of the grill not substantially greater than 50°, so that the air passing through the passages will not break away from the inner walls and forward faces of the imperforate portions but will follow the contour of the inner walls and the forward faces of said imperforate portions and be discharged substantially laterally across the discharge face of the grill.

2. A grill comprising a plate provided with a flat front discharge face and having a series of tongue portions struck rearwardly therefrom and defining an arcuate series of air passages separated by imperforate portions arranged around a central portion closed to the outward escape of air, all of the imperforate portions lying in the same plane and forming said front discharge face, one side face of each tongue portion forming an outer wall for an air passage, the other side face of the same tongue portion forming an inner wall for the next adjacent air passage, the inner walls being shaped to direct the air passing through said passages against the outer walls, the outer walls having an angle with respect to said discharge face of the grill not less than 40° or more than 50°, so that the air passing through the passages will not break away from the inner walls and forward faces of the imperforate portions but will follow the contour of the inner walls and the forward faces of said imperforate portions and be discharged substantially laterally across the discharge face of the grill, said grill having an effective substantially flat front marginal face of at least substantially one inch in width, outwardly of said passages and imperforate portions.

3. A grill comprising a plate provided with a flat front discharge face and having a series of tongue portions struck rearwardly therefrom and defining a series of air passages separated by imperforate portions, all of the imperforate portions lying in the same plane and forming said front discharge face, said air passages being at least six inches long, one side face of each tongue portion forming an outer wall for an air passage, the other side face of the same tongue portion forming an inner wall for the next adjacent air passage, the inner walls being shaped to direct the air passing through said passages against the outer walls, the outer walls having an angle with respect to said discharge face of the grill not substantially greater than 50°, so that the air passing through the passages will not break away from the inner walls and forward faces of the imperforate portions but will follow the contour of the inner walls and the front discharge faces of said imperforate portions and be discharged substantially laterally across the discharge face of the grill.

ALFRED L. GREENLAW.
